Attorney

UNITED STATES PATENT OFFICE

RICHARD LESTER WILCOX, OF WATERBURY, CONNECTICUT, ASSIGNOR TO THE WATERBURY FARREL FOUNDRY AND MACHINE COMPANY, OF WATERBURY, CONNECTICUT, A CORPORATION OF CONNECTICUT

METHOD FOR TRIMMING BLANKS

Original application filed February 13, 1928, Serial No. 254,093. Divided and this application filed February 8, 1930. Serial No. 426,821.

This invention relates to means and method for trimming blanks, whereby the heads thereof may be given a polygonal cross section, such as square, hexagonal or octagonal shape, or a cross section having flat sides or 5 the like, the term "polygonal" as used herein including all such shapes.

It is the object of this invention, among other things, to give such trimmed cross section to a blank by an entire cutting of the metal without tearing it, thus producing a clean and unbroken cut surface on the blank.

These, and other desirable objects of the invention, are obtained by first passing a cutting die over the head of the blank so as to trim the same for a portion of its length, and thereafter holding the cutting die while the head is projected therethrough.

The details and arrangement of parts used in my new and improved means and method 20 for trimming blanks will be apparent from an inspection of the accompanying drawings in connection with the description herein, and wherein a preferred embodiment of the means and method is disclosed for the purpose of 25 imparting an understanding of the same.

This application is a division of the subject matter of an application filed February 13, 1928, Ser. No. 254,093, now Patent No. 1,748,321 issued February 25, 1930.

In the drawings, wherein like characters of reference indicate corresponding parts in the several figures;

Figure 1 is a sectional elevation of the 35 punch and die of a trimming machine and adjacent parts in the relative positions occupied by them as the blank to be trimmed is placed therebetween;

Figure 2 is a similar view showing the 40 shank of the blank projected into the punch and the underside of the head against the outer end thereof with the cutting die in position to begin the cutting operation;

Figure 3 is a similar view with the die and 45 punch when adjacent to each other; and

Figure 4 is a view with the parts in substantially the same position as in Figure 3, except that the trimmed blank has been projected through the die by the knockout mechanism.

Referring to the drawings, 10 indicates the punch having an opening 11 therein of substantially the same size as the shank 12 of the blank, which is held by any convenient means in a punch holder 13; 14 is the gate of the trimming machine, which reciprocates in the usual manner toward and away from the punch holder 13.

Within the gate is a backing block 15, having an opening 16 therein, and connected therewith is the die plate 17 upon which is a die holder 18. Secured in the die plate by any convenient means is the trimming die 19. The opening 20 in this die is substantially the same shape in cross section as that 65 of the finished head of the blank.

In operation the blanks are successively presented with their axes coincident with the openings 11 and 20, substantially as shown in Figure 1, with the head adjacent to the 70 trimming die. Thereafter, during the movement of the parts, the open space between the punch and die is reduced until they are in the position substantially as shown in Figure 2. During this time the pressure upon 75 the face of the head 21 of the blank is such that the shank 12 is forced into the opening 11 in the punch and the end face of the head abuts against the outer face of the punch 10.

The continued movement of the parts 80 causes the die 19 to pass over the die 21 of the blank until the opposite faces of the punch and die are in substantially the relative position shown in Figure 3, when the punch and die are in rest positions. During 85 this latter movement the head of the blank is trimmed for a portion of its length as the trimming die passes thereover.

The chip, fin or shaving 22 formed around the head by the trimming die occupies the 90 space between the faces of the die and punch. While the punch and die are at rest and in these relative positions, the knockout rod 23 moves forwardly, engages the end of the shank 12, if not already in contact therewith, 95 and projects the blank through the opening 20 in the die and the finished product 24 drops through the opening 16. The passage of the head of the blank through the die under the impulse of the knockout mech- 100

anism causes the die to complete the trimming operation and the fin 22 drops from between the punch and die as the space therebetween is increased by the movement of the parts for the next succeeding operation.

Thus, relatively to the punch, the blank is trimmed by two separate actions; first, while the blank is at rest in the punch and the space between the punch and die is being reduced; and second, while the punch and die are at rest and the blank is in motion through the die under the pressure of the knockout mechanism.

One portion of the trimming operation is thus performed while the space between the die and punch is being reduced and the remainder of the trimming while the punch and die are in a substantially fixed relative position.

What I claim as new and desire to secure by Letters Patent, is:

1. The method of trimming the heads of screws, bolts and the like, which consists in bringing the head of a previously headed blank into contact with a head trimming die, moving the trimming die with the blank until the underside of the head thereof engages an abutment and is supported by the shank of the bolt within an opening of substantially the same size thereof and thereafter continuing the movement of the trimming die over the head of the blank for a portion of the length of the head and thereby trimming the head for a portion of its length only and finally trimming the untrimmed portion of the head by moving the blank away from the abutment and through the now stationary trimming die.

2. The method of trimming the heads of screws, bolts and the like, which consists in bringing the head of a previously headed blank into contact with a head trimming die, moving the trimming die with the blank until the underside of the head thereof engages an abutment and thereafter continuing the movement of the trimming die over the head of the blank until it has trimmed the same for a portion of its length and finally trimming the untrimmed portion of the head by moving the blank away from the abutment and through the now stationary trimming die, the blank from the time it is first engaged by the trimming die until completely trimmed travelling in two diametrically opposite directions.

In testimony whereof, I have hereunto affixed my signature.

RICHARD LESTER WILCOX.
